CLAIM

We claim the ornamental design for a bandage release liner having a decorative parting line, as shown and described.

DESCRIPTION

FIG. 1 is a plan view of a first embodiment of a bandage release liner having a decorative parting line showing our new design;

FIG. 2 is a first side view of this first embodiment;

FIG. 3 is a second side view of this first embodiment, opposite the first side view;

FIG. 4 is a plan view of a second embodiment of a bandage release liner having a decorative parting line showing our new design;

FIG. 5 is a first side view of this second embodiment; and, FIG. 6 is a second side view of this second embodiment, opposite the first side view.

The dash-dot-dot-dash broken lines in the drawings depict the bounds of the claim and form no part of the claimed design. All other broken lines showing the backing and absorbent pad of the adhesive bandage are included for the purpose of illustrating environment and form no part of the claimed design.
